JOINT CONSTRUCTION

William F. Aschinger, Columbus, Ohio, assignor
to The Columbus Show Case Company, Colum-
bus, Ohio, a corporation of Ohio

Application December 14, 1942, Serial No. 469,024

2 Claims. (Cl. 20—92)

This invention relates to splice joints, having particular reference to improved means for uniting and retaining in secured assembled relationship a plurality of angularly disposed members.

In certain of its more specific aspects, the invention is concerned with an improvement in the frame construction of merchandise display cases. In such cases, use is made of a plurality of relatively angularly extending frame bars having interfitting end portions which are adapted to be rigidly united for the purpose of effecting the support of glass or other panels. The mechanical arrangement of such frame bars results in three of such bars merging into a common joint, each of the bars being disposed in perpendicular relationship with respect to the remaining bars. Because of this situation, considerable difficulty is encountered in providing a substantial means for permanently uniting such joints, so that the same will not separate or weaken structurally when subjected to the stresses of practical usages.

Accordingly, it is the object of the present invention to provide an improved joint construction between the overlapping and interfitting ends of a plurality of frame bars when such bars are disposed in severe angular relationship with respect to each other.

It is another object of the invention to provide an improved metallic splice member having angularly extending arms, each of which being of dovetail cross sectional formation and received within correspondingly formed slots provided in the adjacent ends of angularly extending frame bars, the arms of said splice member being fastened to the contiguous portions of the frame bars to hold and maintain the latter in relatively secured order.

A further object of the invention resides in providing the metallic splice member with integral webs or fins which are adapted to be disposed between the contiguous faces provided by the meeting ends of three or more converging frame bars, whereby to enhance the strength of the mechanical union between the adjoining frame bars and improve the external appearance of the completed joint.

For a further understanding of the invention, reference is to be had to the following description and the accompanying drawing, wherein:

Fig. 1 is a perspective view of one of the upper corners of a display case, with said bars constructed in accordance with the present invention;

Fig. 2 is a detail perspective view of the splice member used in uniting the adjacent ends of the frame bars;

Fig. 3 is a similar view of the splice member when viewed from the inner side thereof;

Fig. 4 is a similar view disclosing the splice member actively positioned;

Fig. 5 is a vertical sectional view on the plane disclosed by the line V—V of Fig. 1;

Fig. 6 is a horizontal sectional view taken through the joint construction on the plane indicated by the line VI—VI of Fig. 1;

Fig. 7 is a detail sectional view on the line VII—VII of Fig. 5;

Fig. 8 is a view similar to Fig. 7 but disclosing the top glass panel of the display case in a plane higher than that of the corresponding panel shown in Fig. 7;

Fig. 9 is a fragmentary perspective view disclosing the splice-receiving end of one of the frame bars.

Referring more particularly to the drawing, the numeral 1 designates a merchandise display case, the same being provided with frame bars 10 for the support of glass panels 11. Since the present invention is concerned with the construction of the corner joints for such frame bars, the drawing illustrates a single composite joint, particularly the joint used at one of the upper corners of the case.

As indicated, the joint comprises, in each case, a vertical frame bar 10a, and horizontally extending bars 10b and 10c, each of the bars being disposed in appropriate perpendicular relationship with respect to each of the remaining bars. Each of the bars is longitudinally rabbeted at both sides to provide seats for the reception of the marginal edges of the panels 11 and clamping blocks 13 (Figs. 7 and 8), of a conventional nature, may be used for retaining the panels in firm engagement with such seats.

The ends of the frame bars are reversely beveled as at 14 in order that the ends of the bars may overlap the corresponding ends of adjacent bars, as shown in Figs. 1 and 4, and, as indicated in Fig. 9, each bar at the end thereof is provided with an inwardly disposed longitudinally extending recess or socket 15, which is preferably of dovetailed transverse configuration.

Cooperative with this construction, is a metallic splice member designated generally by the numeral 16 in the drawing. This member is of tri-armed construction, being formed with arms 17a, 17b and 17c integrally joined at their ad-

adjacent ends and adapted for reception within the recesses or sockets 15 of the frame bars 10a, 10b and 10c, respectively. Said arms preferably are of dovetail cross sectional configuration in order that the same may be slidably inserted within the recesses or sockets 15 and will possess close-fitting engagement with the wall surfaces of said sockets. Each of the arms is formed with transverse openings 18 which receive the countersunk heads of fastening screws 19, whereby each of said arms is firmly secured to its complementary frame bar.

In order to produce a finished appearance and in addition, a strong mechanical construction, each of the splice members is formed with integral web extensions 20, the latter occupying angular planes corresponding with the beveled faces 15 of the frame bars, the said extensions being positioned between said beveled faces in order to protect the latter, to prevent splintering or roughness on the part of the thin walled edges of the beveled regions 14 of said frame bars and to augment the mechanical strength and to improve the external appearance of the construction generally.

In view of the foregoing, it will be seen that the present invention provides an improved splice or spline means for uniting the mitered overlapping ends of show case frame bars or in other capacities wherein the frame bars extend in angular relation with respect to each other. The corner or joint construction is particularly adapted for frame bars composed of wood. However, other materials may be used, such as the moldable plastics or, in certain instances, metal. The construction is, of course, subject to considerable modification without departing from the fundamental features of the invention. For instance, in Fig. 8, the horizontal upper glass panel 11a is disposed in a plane above that occupied by the corresponding panel in the construction disclosed in Fig. 7. Often, in show case design, it is desirable that the upper surface of the top glass panel be above the plane of the top surface of the sup-

porting frame structure, so that articles will not catch on the edge of the frame structure. Other variations or modifications will be apparent to those skilled in the art and therefore the right is reserved to employ all such variations of my invention that may be said to fall fairly within the scope of the following claims.

I claim:

1. Joint construction comprising three bars, each of said bars being disposed in perpendicular relationship with respect to the remaining bars, said bars having overlapping mitered ends, the inner side of each of said bars contiguous to the end thereof being formed with a longitudinally extending socket, an externally concealed metallic splice composed of three integrally united arms, said arms being receivable within the sockets of said bars and disposed in planes corresponding to those of the bars, removable fastening means for precluding relative movement between said bars and splice arms, and integral web extensions formed with said splice member, said extensions being disposed between the mitered overlapping ends of said frame bars.
2. Joint construction comprising three bars, each of said bars being disposed in perpendicular relationship with respect to the remaining bars, said bars having overlapping mitered ends, the inner side of each of said bars contiguous to the end thereof being formed with a longitudinally extending socket, a metallic splice composed of three integrally united arms, said arms being receivable within the sockets of said bars and disposed in planes corresponding to those of the bars, removable fastening means for precluding relative movement between said bars and splice arms, each of said arms being of dovetailed transverse configuration in conformity with the same configuration of said sockets, and integral web extensions formed with said splice member, said extensions being disposed between the mitered overlapping ends of said frame bars.

WILLIAM F. ASCHINGER.
